United States Patent Office.

BENJAMIN HOGAN, OF ALBANY, NEW YORK.

Letters Patent No. 75,760, dated March 24, 1868.

IMPROVEMENT IN HAT-CONFORMATORS.

The Schedule referred to in these Letters Patent and making part of the same.

TO ALL WHOM IT MAY CONCERN:

Be it known that I, BENJAMIN HOGAN, of the city and county of Albany, State of New York, have invented a new and improved Hat-Conformator, by which the vertical shape and size of human heads are taken; and I do hereby declare that the following is a full, clear, and exact description thereof, reference being had to the accompanying drawings, consisting of Plates I and II, and the letters of reference thereon, indicating the several parts, in which—

Figure 1 represents a section of the instrument in perspective, with improvements.

Figure 2 represents a vertical view of a section from the top.

Figure 3, an end section of size-indicator.

Figure 4 is a side elevation of finger-supporting and bearing-rim and standard.

Figure 5 is an end view of upper and lower angles of fingers, their guides, &c.

Figure 6 is a longitudinal cross-section of instrument.

Figure 7 is a lateral section of the same.

Figure 8 is a vertical section of the same with bearing-rim removed.

The nature of my invention consists in providing the ordinary hat-conformator now used by hatters with a second rim, which may be moved in a vertical direction at will, and securely holds the fingers or arms fixed in their new-assumed positions; also in providing a suitable register or indicator, upon which the size of the head is registered by means of a finger or pointer, operated by the fingers or arms through the medium of a cord, or equivalent means.

To enable others skilled in the art to make and use my invention, I will proceed to describe it, in reference to the accompanying drawings, and the letters of reference marked thereon, the same letters indicating like parts.

A A, figs. 1, 2, 3, 4, 5, 6, 7, and 8, represent the main or supporting rim, to which are attached the standards S S, figs. 4, 6, and 7, on the top, and attached to the said standards is the oval crown C. Placed around inside the opening of the supporting rim A are the fingers F F, forty or more in number, with their upper and lower angle-pieces. The upper angle-pieces, a a, extending back and resting upon the crown C, are held in place by the crown-rim D, figs. 1, 2, 5, 6, and 7, while the lower angle-pieces, b b, extending forward, rest upon the rim A, and are secured by the guides g g, or their equivalent. The fingers thus placed and secured, have freedom to move outward, and are kept inward against the crown C by the elastic band e or e'. The said elastic band may be made of rubber or coiled spring-wire, or any other suitable substance. Over and within the rim A is placed the pressing-rim B B, figs. 1, 2, 4, 6, and 7, supported by a number of spiral springs, c, or otherwise elastically seated. This bearing-rim, B when pressed down, is held by two catches, d d, placed at either side, which holds the rim in pressure. Made through or attached to the fingers F F, or either of their angle-pieces, are the cord-holes x, or eyes i, figs. 1, 2, 4, 6, and 7, placed at proper points. Through the said eyes or holes, communicating at the front of the instrument, is passed the cord, m, which encircles all the fingers, and returning to the front again, the two ends of the cord are then passed through the eyes placed in the ends of the arms p p, figs. 1, 2, and 6. The said arms carry the cords under the pulley G, from whence the cords pass upwards and are coiled around the said pulley, and secured to the regulating-screw n, fig. 6. The pulley G turns with its shaft f, and is kept taut by the coiled spring r, figs. 2 and 3, fastened to the pulley-shaft f and to one side of the spring-chamber h. Front of the spring-chamber is the dial-plate H, with whole, half, and quarter sizes marked thereon. To the end of the pulley-shaft, projecting through the dial-face, is attached the pointer t, which, when the instrument is being operated, will move over the face, and indicate the size to which the fingers have been distended.

To operate this instrument, the instrument is placed on the head, and gently pressed in a vertical direction, and by the pressure, the fingers F F are distended to a capacity which will be equal to and will conform with the irregular oval line of the said head, and while the said fingers are being distended, the cord m is being lengthened and its circumference enlarged, and uncoiling from the pulley G, the cord m moves the pointer t to and over the number of the size marked thereon, and the indicated size will correspond with the size of the head measured.

If desirable, the fingers *F F* may be held in position as will indicate the shape of the head by pressing down the bearing-rim *B* upon the angle-pieces *b b*, when the snap-bolts *d d* will shoot forward and hold the said rim in pressure. While the fingers are thus held, the shape of the head can be duplicated, and transferred to paper by placing a piece of paper in the crown-cover *J*, and pressing the said cover, with its paper, down upon the points *z z*, placed on the upper angle-pieces *a a*.

The old head-conformator gives only the irregular oval surface-line around the head, and that, too, while it is on the head, when the paper for transfer must be punctured, and resumes its original smaller regular oval when removed, and does in no case indicate the size of the head.

The advantages of this instrument over the old are these: first, the size of the head is accurately taken, and secured for any length of time desired; second, the shape of the head may be preserved as long as desired; third, the hat-fitting instrument (used for fitting the hat to the head) can be set up, if desired, directly from the distended fingers, without recourse to the duplicating-process by paper.

Having described my invention, I do not claim the lower rim, nor the fingers, of themselves, or in their peculiar formation, nor the crown or crown-cover; but

What I claim, and desire to secure by Letters Patent, is—

1. The pressing-rim *B*, spring *C*, and holding-catches *d d*, combined and arranged substantially as and for the purpose specified.
2. In combination with the measuring-fingers or arms of a hat-conformator, the ring or band *B*, or equivalent device, for securing the said arms in fixed position, substantially as described.
3. In combination with a hat-conformator, an indicator, or equivalent registering-device, upon which is indicated the size to which the measuring-arms are distended, substantially as described.
4. The cord or chain *m*, fingers *F*, and indicator *H*, arranged and operating as described.

BENJAMIN HOGAN.
